UNITED STATES PATENT OFFICE.

WILLIAM BARTHOLOMEW AND FRITZ BALZER, OF CHICAGO, ILLINOIS, ASSIGNEES TO
TROY LAUNDRY MACHINERY COMPANY, LIMITED, OF CHICAGO, ILLINOIS, A COR-
PORATION OF NEW YORK.

AUTOMATIC PRESSURE-ROLL CONTROL FOR MANGLES.

1,085,524.

Specification of Letters Patent.

Patented Jan. 27, 1914.

Application filed April 17, 1912. Serial No. 691,404.

To all whom it may concern:

Be it known that we, WILLIAM BARTHOLOMEW, a citizen of the United States of America, and FRITZ BALZER, a subject of the Emperor of Germany, residing at Chicago, county of Cook, State of Illinois, have invented certain new and useful Improvements in Automatic Pressure-Roll Control for Mangles, of which the following is a specification, reference being had therein to the accompanying drawing.

This invention relates to certain new and useful improvements in mangles, and more particularly to means for automatically controlling the raising and lowering of the pressure rolls and is an improvement upon Patent #909,312, issued to Sivert Moe, January 12, 1909; the object being to improve and simplify the construction for raising and lowering the rolls and to provide positive means for cutting off the power when the rolls have reached the desired position, in respect to the heating drum.

Another object of the invention is to provide automatic means for operating the roll-shifting mechanism which is so constructed that the same can be operated either by power or manually.

Another object of the invention is to provide means whereby the automatic means can be thrown out of operation when it is desired to bring the gears of the rolls and cylinder out of mesh.

A still further object of the invention is to provide a construction which can be readily applied to any of the well-known makes of mangles now in use.

Other and further objects and advantages of the invention will be hereinafter set forth and the novel features thereof defined by the appended claims.

In the drawings—Figure 1, is an end elevation of a portion of a mangle showing a portion of our improved controlling mechanism applied thereto; Fig. 2, is a front elevation of a portion of the mangle partly in section, showing the connection between the operating mechanism and roll-supporting members; Fig. 3, is an enlarged section

through the sprocket and arm; Fig. 4, is a section taken on the line 4—4 of Fig. 3; Fig. 5, is a rear elevation of a portion of the operating mechanism, the frame of the mangle being broken away; Fig. 6, is an enlarged view of the operating mechanism partly in section, showing the mangle broken away; and Fig. 7, is a detail top plan view of the driving gears and clutch. Fig. 8, is a detail view of the tension means for centering the clutch member when in neutral position; and Fig. 9, is a detail view of our improved pressure indicator.

In the drawing, 1 indicates the frame of the mangle which is provided with suitable bearings 2, in which the trunnions 3 of the hollow drum or cylinder 4 is revolvably mounted, said frame having an arched portion 5 which extends to the top of the drum, and is provided with suitable guide members 6 in which are mounted the pressure roll 7 carrying boxes 8. The boxes 7 are provided with supporting members 9 of the ordinary construction, having depending end portions carrying laterally projecting pins 9 which extend through obliquely arranged slots 10 formed in a segment 11 which is mounted upon each of the trunnions of the cylinder in order that the same can be oscillated thereon, as will be hereinafter fully described.

Centered to one end of the segment 11 is an operating rod 12 which is connected at its free end to a wrist pin 13 carried by a disk 14 mounted upon the shaft 15 journaled in suitable bearings of the frame 1. The above description being given so that the operation of our improved mechanism will be readily understood when applied to a mangle of this character and it is of course understood, that when the construction of mangle is changed, the mechanism will be likewise changed in order to allow the same to be readily applied thereto.

From the above description, it will be seen that when the shaft 15 is rotated in either direction, the pressure rolls will be raised and lowered, as the case may be, this construction being substantially the same as

disclosed in the above mentioned patent to Moe.

In order to provide means for manually operating the pressure rolls a shaft 16 is mounted in suitable bearings 17 carried by a plate 18, fixed to the frame 1, said shaft being provided with a wheel 19 at its outer end by which the shaft can be manually rotated. The shaft 16 is also provided with a worm 20 meshing with a worm-gear 21 fixed on the shaft 15 in order to oscillate the disk 14 and it will be seen that when rotated to the right, the operating rod 12 will be drawn downwardly in order to oscillate the segment 11 so as to cause the pressure rolls to be brought into contact with the drum 4, when rotated in a reverse direction the pressure rolls will be thrown out of contact.

Secured to the frame 1 is a bracket 22 in which a power shaft 23 is mounted at right angles to the shaft 16 which is adapted to be rotated continuously by a sprocket-chain 24, passing over sprocket wheels 25 and 26, the sprocket wheel 25 being fixed on the shaft 23 and the sprocket wheel 26 being fixed on the shaft 27, which is driven by the driving mechanism of the mangle not shown. Loosely mounted upon the shaft 23 are spaced beveled pinions 28 and 29 which mesh with a bevel gear 30 fixed on the inner end of the shaft 16 said pinions being provided with clutch portions 31 and 32 adapted to co-act with the double clutch member 34 feathered upon the shaft 23 whereby either one of said pinions can be locked to the driving shaft in order to rotate the bevel gear 30 in either direction in order to raise or lower the pressure rolls.

For shifting the clutch member 34 so as to lock either of the bevel pinions of the power shaft 23 we provide the frame 22 with a pivoted clutch-throwing yoke 35, which is provided with a slotted extension 36 through which extends a bolt 37, carried by the lower end of a lever 38 pivotally mounted upon the bracket 22 as shown at 39, said lever extending upwardly and having its free end connected to a crank-arm 40 carried by a shaft 41 mounted in suitable bearings 42 of a bracket 43 fixed to the frame 1 in a plane above the shaft 16, as clearly shown. For operating the shaft 41, we provide the outer end of the same with a lever 44 whereby the shaft can be rocked in its bearings in order to shift the clutch member. To provide tension means for centering the clutch member when in neutral position, we provide the shaft 41 with an arm 45 having a segment 46 at its end provided with a projection, the edges of which co-act with the free ends of a bowed-spring 47, as clearly shown in Fig. 8, and in dotted lines in Fig. 5. While we have shown this construction, it is of course understood, that

it is not essential, as the mechanism herein-after fully described for returning the clutch member to neutral position, is sufficient.

Supported by the shafts 16 and 41 is a casing 48 inclosing sprocket wheels 49 and 50 carried by the shafts 16 and 41, the sprocket 49 being loosely mounted on the shaft 41 and the sprocket 50 fixed on the shaft 16 and passing over these sprockets is a sprocket-chain 51, as clearly shown in Figs. 2 and 6, whereby the sprocket 49 will be rotated when the shaft 16 is operated either by power or by hand. The sprocket 49 is provided with a projection 52 which is adapted to engage a spring-pressed pin 53 mounted in a sleeve portion 54 of an arm 55 fixed on the shaft 41, said pin being provided with a knob 56 at its outer end by means of which the same can be drawn out of the path of travel of the projection 52, of the sprocket 49 in order to allow the sprocket to continue its rotation so as to prevent the operation of the automatic means for returning the clutch member into neutral position. This provides means for throwing the pressure rolls into such position that the gears for driving the rolls will be thrown out of engagement with the cylinder gear whereby the rolls can be repaired or recovered. The sleeve portion 54 of the arm 55 travels in a curved slot 64, formed in the casing 48, as clearly shown in Fig. 2.

In connection with the above mentioned mechanism, we provide a pressure indicator which is connected to one of the pressure roll supports and as herein shown, comprises an arm 57 carrying an operating rod 58 which is adjustably mounted therein, as shown at 59, the upper end of the rod being connected to the crank arm of a pointer shaft 60. The pointer shaft is provided with a suitable pointer 61 traveling over a dial 62, supported by a bracket 63, secured to the frame.

The operation of the mechanism for raising and lowering the pressure rolls is as follows: Supposing that the mechanism is in the position as shown in the drawing, by throwing the lever 44 to the left or over the designation "On" marked on the casing 48, the clutch member 34 will be locked to the bevel pinion 31 causing the same to rotate therewith, which in turn will rotate the bevel gear 30 in the direction shown by the arrow, so as to cause the worm meshing with the gear 21 to rotate the shaft 15, carrying with it, the disk 14 which will draw down on the operating rod 12 and cause the segment 11 to oscillate upon its pivot so as to bring the oblique slots into such a position that the pressure coils will be drawn down upon the cylinder or drum. The size of the sprocket 49 in comparison with the sprocket 50 is such that a complete turn of the large

sprocket will be equal to the distance of travel of the operating rod in order to obtain the desired pressure, whereby the projection 52, carried thereby will be brought into engagement with the pin 53 of the arm 55 so as to rock the shaft 41 and return the lever 44 into a central or neutral position, which in turn through the link connections will throw the clutch member 34 into neutral position so as to release the driving mechanism and the operating mechanism will be brought to a standstill. It will be seen that by this construction, the driving mechanism will be thrown out of operation at the desired time and that by changing the sprockets for sprockets of different sizes, the shifting of the clutch can be regulated. The operation of lowering the rolls is the reverse of the raising, and as the sprocket 49 is loose upon the shaft 41, the same runs free until the projection carried thereby is brought into engagement with the pin of the arm fixed on the shaft, which will throw the clutch member into neutral position. By drawing outwardly upon the knob 56 and operating the hand-wheel 19, the pressure rolls can be raised and lowered manually and when it is desired to mechanically control the same, it is only necessary to release the knob and oscillate the lever 44 into either the off or on position, as the case may be, which in turn will throw the clutch into engagement with one of the bevel pinions so as to cause the worm-shaft to rotate in the desired direction so as to raise or lower the pressure rolls.

From the above description it will be seen that we have provided automatic means for controlling the raising and lowering of the pressure rolls, the connection between the worm-shaft and lever shaft forming means for automatically throwing the driving mechanism out of operation when the pressure rolls have reached either of their positions.

We claim:

1. In a mangle, the combination with a mechanism for raising and lowering the pressure rolls, a driven shaft for actuating said mechanism, a power control for said driven shaft, a lever actuated shaft, a connection between said lever shaft and power control, means revolving loosely upon said lever shaft actuated by the raising mechanism and coacting periodically with said shaft for automatically returning said power control to neutral position.

2. In a device of the kind described, the combination with a plurality of movably mounted pressure rolls, of a shaft, a member carried by said shaft, an oscillating member for raising and lowering said rolls, a connection between said oscillating member and the member carried by said shaft, gearing for operating said shaft, a continu-

ously rotating shaft for operating said gearing, a control for said driving means, a member loosely carried by said control, a driving connection between said loosely mounted member and gearing, and co-operating means carried by the control and loosely mounted member for returning said control to neutral position after the adjustment of said rolls.

3. In a mangle, the combination with a plurality of movably mounted pressure rolls, of an oscillating member for actuating said pressure rolls, a shaft, a connection between said shaft and oscillating member, a second shaft, gearing connection between the first-mentioned and second-mentioned shafts, a driven shaft, gearing connection between the second shaft and the driven shaft, a clutch mounted upon the driven shaft, a control for said clutch, means carried by said control co-operating therewith predeterminedly and a connection between said second shaft and the means for automatically returning said clutch to neutral position after the adjustment of said pressure rolls.

4. In a mangle, the combination of a plurality of movably mounted pressure rolls, of an oscillating member for actuating said rolls, a shaft, a disk carried by said shaft, a connection between said disk and oscillating member, a second shaft, gearing connection between the first-mentioned and second-mentioned shaft, a driven shaft, gearing connection between the second shaft and the driven shaft, a clutch on said driven shaft, a lever for actuating said clutch, a lever-actuated shaft for controlling said lever, a member loosely mounted upon said lever-shaft, a driving connection from the second shaft to said member, and means carried by said member for actuating said shaft to automatically return the clutch to neutral position after the adjustment of said rolls.

5. In a mangle, the combination with a mechanism for raising and lowering the pressure rolls, a driven shaft for actuating said mechanism, a clutch for controlling said driven shaft, a lever actuated shaft, a connection between said lever shaft and clutch, for actuating the same, and means revolving loosely upon said lever shaft actuated by the raising mechanism, for automatically returning said clutch to neutral position.

6. In a mangle, the combination with mechanism for raising and lowering the pressure rolls, of power driven gears for actuating said mechanism, a clutch for controlling said gears, a lever shaft, a connection between said lever shaft and clutch, a member loosely mounted upon said lever shaft, a driving connection between said member and mechanism, a projection upon said member, and an arm upon said lever shaft adapted to be engaged by said projection for returning said clutch to neutral

position after the adjustment of said pressure rolls.

7. In a mangle, the combination with mechanism for raising and lowering the pressure rolls by hand, of a power driven shaft, gears loosely mounted upon said power driven shaft, a gear carried by said mechanism meshing with said gears, a clutch for locking either of said gears to said driving shaft, a lever shaft, a connection between said lever shaft, and clutch, an arm carried by said lever shaft, a member loosely mounted upon said lever shaft, a driving connection between said member and mechanism, and a projection upon said member arranged to engage said arm for oscillating said lever shaft to return said clutch to neutral position after the adjustment of said rolls by power.

8. In a device of the kind described, the combination with a shaft, of a second shaft, a gearing connection between said first shaft and second shaft, a gear carried by said second shaft, a continuously rotating shaft, arranged at right angles to said second shaft, gears loosely mounted upon said rotating shaft meshing with the gear upon said second shaft, a clutch for locking either of said gears to said rotating shaft, a lever shaft, a crank arm fixed to said lever shaft, a lever connected to said clutch, and to said crank arm, a sprocket loosely mounted upon said lever shaft, a sprocket fixed on said second shaft, a chain passing over said sprockets, an arm carried by said lever shaft, and a projection on said first-mentioned sprocket adapted to engage said arm for rocking said lever shaft to return said clutch to neutral position.

9. In a device of the kind described, the combination with manually operated mechanism for raising and lowering a plurality of slidably mounted members, of a gear carried by said mechanism, a driven shaft, gears carried by said driven shaft, meshing with said gear, said gears being provided with clutch members, a double clutch member feathered upon said driven shaft, a yoke arm for sliding said clutch member, a lever for actuating said yoke arm, a lever shaft for actuating said lever, and a connection between said mechanism and lever shaft, for automatically returning said clutch member to neutral position after the adjustment of said slidably mounted members.

10. In a mangle, the combination with a drum, of a plurality of pressure rolls mounted to move to and from said drum, a shaft, an oscillating member for actuating said pressure rolls, a member mounted upon said shaft, a connection between said member and oscillating member, a gear carried by said shaft, a second shaft carrying a worm meshing with said gear, a wheel for manually operating said second shaft, a bevel gear

carried by said second shaft, a driven shaft, gears loosely mounted upon said driven shaft meshing with the gear of the second shaft, said gears being provided with clutch members, a double clutch member feathered upon said driven shaft, a clutch actuating mechanism, a loosely mounted member carried by said mechanism, a driving connection between said loosely mounted member and the second shaft, and coöperating means carried by the loosely mounted member and actuating mechanism for returning said clutch to neutral position, after the adjustment of said rolls.

11. In a mangle, the combination with power driven means for raising and lowering the pressure rolls thereof, of a clutch for controlling said driving means, a yoke arm for sliding said clutch, a pivoted lever for actuating said yoke arm, a lever shaft, a crank arm carried by said lever shaft connected to said lever, and mechanism carried by said lever shaft, and actuated by the raising mechanism for returning the clutch to neutral position after the adjustment of said pressure rolls.

12. In a mangle, the combination with a plurality of pressure rolls, of an oscillating segment for actuating said rolls, a shaft, a member carried by said shaft, a connection between said member and said oscillating segment, a second shaft, a gearing connection between said shaft and said second mentioned shaft, power driving means for said second shaft, a control for said power driving means, a member loosely mounted upon said control, a connection between said second shaft and loosely mounted member, and coöperating means carried by the loosely mounted member and control, whereby said power controlling means will be returned to neutral position after the adjustment of said rolls.

13. In a mangle, the combination with a drum, a plurality of pressure rolls co-acting therewith, an oscillating member for moving said rolls to and from said drum, a shaft, a member carried by said shaft, a connection between said member and said oscillating member, a gear carried by said shaft, a worm meshing with said gear, a shaft carrying said worm, a gear carried by said shaft, a driven shaft, gears carried by said driven shaft meshing with the last-mentioned gear, a clutch for locking either of said gears to said driven shaft, a lever shaft, a connection between said lever shaft and clutch, a sprocket carried by said second shaft, a sprocket loosely mounted upon said lever shaft, an arm fixed to said lever shaft, a spring-pressed pin carried by said arm and a projection carried by said sprocket upon the lever shaft adapted to co-act with said pin and return said clutch to neutral position, after the adjustment of said rolls.

14. In a mangle, the combination with a pair of shafts, a wheel for actuating one of said shafts, a lever for actuating the other shaft, a sprocket fixed on one of said shafts, a sprocket loosely mounted upon the other shaft, an arm fixed to the shaft carrying the loosely mounted sprocket, a projection carried by the loosely mounted sprocket, co-acting with said arm, and a power controlling mechanism connected to said lever shaft.
15. In a device of the kind described, the combination with a continuously rotating driven shaft, of gears loosely mounted upon said shaft, provided with clutch members, a double clutch member feathered upon said driven shaft, adapted to co-act with the clutch members of said gears, a second shaft having a gear meshing with said gears, a lever shaft for actuating said clutch, a member loosely mounted upon said lever shaft, a connection between said second shaft and loosely mounted member, and co-operating means carried by the loosely mounted member and lever shaft for returning said clutch to neutral position.
16. In a device of the kind described, the combination with power driven means, of a control for said power driven means, a rock shaft for actuating said control, and means for automatically cutting off said power at a predetermined time, said means being actuated by a rotary member carried by the rock shaft.
17. In a mangle, the combination with a drum, of a plurality of pressure rolls co-acting therewith, an oscillating member for raising and lowering said rolls, a shaft, a member carried by said shaft, a connection from said member to said oscillating member, a gear carried by said shaft, a worm mounted upon a shaft meshing with said gear, a gear carried upon said worm-shaft, a continuously rotating shaft, gears loosely mounted upon said rotating shaft meshing with said gear, a clutch for locking either of said gears to said driven shaft, a lever shaft for controlling said clutch, rotating means carried by the lever shaft, and actuated by the driven shaft and co-operating means between said rotating means and lever shaft for returning said clutch to neutral position after the adjustment of said rolls.
18. In a mangle, the combination with a drum, a plurality of pressure rolls co-operating therewith, an oscillating member for raising and lowering said rolls, a shaft, a disk carried by said shaft, provided with a wrist-pin, a rod mounted upon said wrist-pin connected to said oscillating member, a worm gear fixed on said shaft, a shaft arranged at right angles to said shaft, a worm carried by said shaft, a bevel gear carried by the worm shaft, a continuously rotating shaft, gears loosely mounted on said rotating
- shaft, provided with clutch members, a double clutch member feathered upon said rotating shaft, a lever shaft, a connection between said lever shaft and clutch, a sprocket fixed on said worm shaft, a sprocket loosely mounted upon said lever shaft, an arm fixed on said lever shaft, provided with a sleeve portion, a spring-pressed pin mounted in said sleeve portion, and a projection carried by the said loosely mounted sprocket adapted to engage said pin for rocking said lever shaft to return said clutch to neutral position after the adjustment of said rolls.
19. In a mangle, the combination with mechanism for raising and lowering the pressure rolls thereof, a driven shaft for actuating said mechanism, a power control for said driven shaft, a shaft, a connection between said shaft and power control, and revolving means independently mounted on said shaft actuated by the raising mechanism for returning said power control to neutral position after the adjustment of said rolls.
20. In a mangle, the combination with mechanism for raising and lowering the pressure rolls thereof, a driven shaft for actuating said mechanism, a power control for said driven shaft, a control shaft, a connection between said control shaft and power control, a member loosely mounted upon said control shaft actuated by said raising mechanism for actuating said control shaft to return said power control to neutral position after the adjustment of said rolls.
21. In a mangle, the combination with mechanism for raising and lowering the pressure rolls thereof, a driven shaft for actuating said mechanism, a power control for said driven shaft, a controlling shaft, a connection between said controlling shaft and power control, means revolving loosely upon said controlling shaft, a driving connection between said means and raising mechanism, said revolving means co-acting periodically with said controlling shaft for automatically returning said clutch to neutral position.
22. In a mangle, the combination with mechanism for raising and lowering the pressure rolls thereof, a driven shaft for actuating said mechanism, a power control for said driven shaft, a rotary shaft, a connection between said shaft and power control, a member independently revolvably mounted upon said shaft actuated by the raising mechanism, and means carried by said member co-acting with the power control for shifting said power control to neutral position after the adjustment of said rolls.
23. In a mangle, the combination with mechanism for raising and lowering the pressure rolls thereof, of driving means for actuating said mechanism, a power control for said driving means, a control shaft hav-

ing a connection with said power control, a revolving member having a driving connection with said raising mechanism, said revolving member co-operating periodically with said control shaft for returning said power control to neutral position after the adjustment of said rolls.

In testimony whereof we affix our signatures in presence of two witnesses.
